UNITED STATES PATENT OFFICE.

FREDERICK WILLMONT DUNNELL, OF SPRINGFIELD, MASSACHUSETTS.

RAILROAD CROSS-TIE.

SPECIFICATION forming part of Letters Patent No. 722,501, dated March 10, 1903.

Application filed July 8, 1902. Serial No. 114,711. (No model.)

To all whom it may concern:

Be it known that I, FREDERICK WILLMONT DUNNELL, a citizen of the United States, and a resident of Springfield, in the county of Hampden and State of Massachusetts, have invented 5 a new and Improved Railroad Cross-Tie, of which the following is a full, clear, and exact description.

This invention has for its object to provide 10 a cross-tie composed mainly of leather and stiffened by a metal core-bar.

The invention consists in the novel construction and combination of parts, as is hereinafter described, and defined in the appended 15 claims.

Reference is to be had to the accompanying drawings, forming a part of this specification, in which similar characters of reference indicate corresponding parts in all the figures.

20 Figure 1 is a perspective view of a metal core-bar that is a detail of the invention. Fig. 2 is a transverse sectional view of the railroad cross-tie substantially on the line 2 2 in Fig. 3. Fig. 3 is a perspective view of one end 25 portion of the cross-tie, showing the core-bar projected therefrom; and Fig. 4 is a view similar to Fig. 3, but showing the flanged end of the core-bar folded upon the end of the tie-body.

30 The invention, briefly described, provides a tie-body molded from granulated or pulverized leather, which may be waste material, and any suitable waterproof cement thoroughly mixed with said material, a core-bar, 35 of plate metal, having novel form being supported in the mold wherein the tie-body is subsequently molded, so that the core-bar may project from each end of the tie-body and said end portions be folded down upon the ends of 40 the tie-body, thus securing the core-bar from longitudinal displacement.

In the drawings, 5 represents the core-bar, and, as shown, it consists of an elongated strip of plate metal, which while in the form 45 of a flat blank is rectangular in contour. The plate-metal blank from which the core-bar is formed has at each end four flanges $a a' a'' a'''$ formed thereon by slitting the material longitudinally an equal distance from the ends, 50 and these slits $b b' b''$ at each end are prefer-

ably spaced apart equally and are parallel with each other. The blank for the core-bar is bent in opposite directions, respectively, in alinement with the slits b in opposite ends and likewise with the slits b'' therein, these bends producing the lateral flanges 5^a , giving the core-bar somewhat the form of the letter Z in cross-section. The core-bar is rendered quite rigid by the provision of the flanges 5^a thereon and is so proportioned in length that 60 when in place within the tie-body the end flanges thereon will project beyond the ends of the tie their full length.

The tie-body 6 is preferably formed with parallel top and bottom surfaces and convexed 65 sides, it being a concretion of granular leather solidified by admixture with any suitable cement that is waterproof and that will harden into a slightly-elastic mass when subjected to heavy pressure while in process of manufacture. Before consolidation of the plastic material in a suitable mold the core-bar 5 is held centered in the mold-space or matrix, so that when the tie-body is molded around the core-bar the latter will be embedded therein at the 70 center, as represented in Fig. 2. After the tie-body 6 is removed from the mold and becomes hardened by exposure to the air the flanges $a a' a'' a'''$ are bent at a right angle in the direction represented by the arrows in 75 Fig. 3, which will fold them flat upon the ends of the tie-body 6, disposing them at each end as represented in Fig. 4, having their inner edges contacting and their outer edges arranged in rectangular form.

80 It will be seen that by provision of the plate-metal core-bar 5 and its combination with the composite tie-body 6 a light strong slightly-resilient tie is produced, which if manufactured of waste leather as a material for the 85 tie-body will be comparatively inexpensive.

Having thus described my invention, I claim as new and desire to secure by Letters Patent—

1. In a composite cross-tie, the plate-metal 90 core-bar, having substantially Z shape in cross-section, and a plurality of foldable flanges at each end thereof.

2. In a composite cross-tie, the plate-metal 95 core-bar having substantially Z shape in cross-

section, and at each end four foldable flanges, formed by three spaced slits formed longitudinally in the core-bar material.

3. A composite cross-tie, comprising a plate-
5 metal core-bar substantially Z shape in cross-
section, and having a plurality of flanges at
each end thereof, a tie-body formed of granular
leather and a suitable cement, adapted to
harden, the core-bar being embedded in the
10 tie-body while the material of said body is

plastic, and the flanges at each end of the core-bar being folded upon the ends of the tie-body to hold said core-bar in place.

In testimony whereof I have signed my name to this specification in the presence of 15 two subscribing witnesses.

FREDERICK WILLMONT DUNNELL.
